ROCKER ADJUSTING MECHANISM

Christopher M. Drew, Harvey, Ill., assignor to General Motors Corporation, Detroit, Mich., a corporation of Delaware

Application May 28, 1956, Serial No. 587,770

5 Claims. (Cl. 123—90)

This invention relates generally to a valve-operating train for use in an internal combustion engine and the like which includes a valve rocker and is particularly concerned with the fulcruming of the rocker and the regulation of clearance in such a train.

In a valve train of the type concerned with here, the valve (usually a "poppet" valve) has a stem portion that extends from the cylinder block. A strong spring between a flange on the stem and the block urges the valve closed or onto its seat. By the aid of a cam arrangement operated from the engine shaft, a push rod transmits motion to one arm of a valve rocker having a second arm which is adapted to engage the top of the valve stem and push the valve off its seat against the biasing action of the valve spring. The different components of such a train are subject to temperature changes which cause their lengths to vary. For this reason it is common to allow slight clearance between the different components of the train when the engine is cold and include a clearance regulator or lash adjuster which automatically regulates or adjusts this clearance so that it is zero regardless of any temperature changes and consequent variations in lengths of the components of the train. Probably the most common present form of such an adjuster or regulator is the so-called hydraulic valve lifter which is usually located in a guide in the cylinder block between the push rod and camshaft of the engine.

One of the difficulties with the use of such regulators is their location which makes them relatively inaccessible for changing out, maintenance and repair since they are located well down in the engine block below the rocker arm and the push rod. Furthermore, due to the hydraulic fluid involved in the operation of hydraulic valve lifters they include a multiplicity of parts with rather critical fits between them. Since a lash adjuster located at the rocker arm pivot is in a relatively accessible position particularly when compared to the location of usual hydraulic valve lifters, it is proposed here to combine such an adjuster with the fulcrum for the rocker arm, and in order to cut down the number of parts and also eliminate the need for critical fits between such parts, make the adjuster mechanical rather than hydraulic. In addition, by combining a mechanical clearance regulator with the rocker fulcrum or pivot, the rocking movement of the rocker may be utilized to cause the regulator to properly function in a unique manner to be hereinafter set forth.

It is, then, broadly an object of this invention to provide a clearance regulator or lash adjuster of an improved mechanical type at the rocker fulcrum.

It is a further object of the invention to provide a combination rocker arm fulcrum and clearance regulator which is adapted to be used in combination with the new types of stamped dish-like rockers found in present high speed, high compression internal combustion engines.

Another object of this invention is to provide a clearance regulator in combination with a rocker fulcrum which utilizes the rocker movement to cause the regulator to function.

For a fuller understanding of the invention and the objects thereof reference is made to the accompanying detailed description and drawings, in which:

Figure 1 is a transverse sectional view through a portion of an internal combustion engine whose valve-operating train includes a rocker and the novel combined fulcrum and clearance regulator in accordance with the invention.

Figure 2 is an enlarged fragmentary view of the engine 10 and the rocker assembly of Figure 1 showing the parts in greater detail.

Figure 3 is an enlarged fragmentary view in section taken substantially on the line 3—3 of Figure 2 to show the relationship between the threads of the members of 15 the rocker arm fulcrum.

Figure 3a is a fragmentary view on an enlarged scale of portions of the mating threads of Figure 3, but with the members arranged in theoretical or hypothetical position to illustrate how the threads are formed so that 20 diametrical or lateral clearance is provided between the members which enables them to move laterally relative to each other.

Figure 4 is a fragmentary view similar to Figure 2 with parts broken away and in section showing a modified version 25 of the invention.

Figure 5 is another fragmentary view with parts broken away and in section showing a further modification.

Figure 6 is a view taken substantially on the line 6—6 30 of Figure 5 showing a detail of the modification of Figure 5.

Figure 7 is another modification of the invention.

Referring now to the drawings, in Figure 1 the engine is illustrated as having a cylinder block and crankcase 1 in which a power piston 2 operates in a cylinder 3. The 35 numeral 4 designates the engine cylinder head in which is reciprocably mounted a poppet valve 5 biased to its closed position by a return spring 6 and movable in the opening direction by a cylinder head mounted valve rocker 7 in response to upward movement of a push rod 40 8 operatively connecting the push rod to an engine-driven cam 9 through a tappet 10. As seen by the embodiment of Figure 2, the rocker 7 is stamped into a cup-shaped form with a hole 11 in the bottom thereof extending in the direction of thrust applied to the rocker by push rod 45 8 and the stem of the valve 5. Pressed in the cylinder block 1 is the lower end of a stud 12 having a shank portion extending in the direction of thrust through the opening 11 in rocker arm 7. The upper end of shank 12 is threaded as at 13 and has screwed thereon a nut 14 50 provided with external threads 15 adjacent its lower end. A body member 16 telescopically associated with nut 14 and shank 12 is provided at its upper end with threads 17 and is threaded on the nut 14 so that an annular chamber 18 is formed around shank 12 between the threaded 55 portions 15 and 17 and the bottom of the member 16. Member 16 is provided at its lower end with a spherical convex bearing surface 19 which cooperates with a similar spherical concave bearing surface 20 in the bottom of rocker 7 to define the rocking axis of the rocker.

60 Turning briefly to Figures 3 and 3a which represent enlarged detail showings of the threads 15, 17 of Figure 2, it will be observed that there is lateral or diametrical clearance between the threads 15 which has been indicated by the symbol C. This lateral or diametrical clearance C allows the members 12 and 16 to slide laterally on the helical threaded surfaces so as to take up the clearance in one or another direction for a purpose which will appear shortly.

65 Returning to Figure 2, it may be seen that located in 70 the annular chamber 18 is a helical coil spring 21 through which the shank 12 extends and whose lower end 22 extends axially and is anchored in a suitable hole tapped

in the bottom of the member 16. The upper end 23 of spring 21 also extends axially and is anchored in the lower end of the portion of the nut 14 carrying the threads 15 in an axially extending passage 24 whose diameter is larger than that of the end 23 and communicates with a passageway 25 in communication with the threaded portions 15, 17. In addition to the lateral or diametric C clearance provided between the threads 15, 17 there is also provided clearance K between the surface defining the opening in the bottom of the member 16 and the outer cylindrical surface of the shank 12. Spring 21 is torsionally loaded so that it tends to wind the body or member 16 downwardly on the threads 15 of the nut 14. Lubricating oil is supplied from an oil gallery 26 in the cylinder head 4 to a passage 27 in the shank 12 leading via a port 28 to the chamber 18. The oil may then pass from the chamber 18 via the passages 24 and 25 to the threads 15 and 17 so as to lubricate these threads and allow the body 16 to turn more easily on the nut 14. This same oil also finds its way between the surfaces 19 and 20 so as to lubricate these latter surfaces.

The operation of the combined fulcrum and clearance regulator is as follows: The function of the regulator is to maintain a small load between the parts of the valve train when the cam follower is on the base circle of the cam. As the temperature and hence the expansion of the parts in the valve train increases the load between the various parts of the train would increase if the adjuster could not compensate for the expansion of the parts until the load would become as great as the valve spring load. Any further expansion of the parts due to further increases in temperature would prevent the valve from seating—an extremely undesirable condition because of the consequent loss of engine power as well as burning of the valves, etc. Thermal contraction of the parts of the train tending to cause lash in the valve-operating train would first remove the small inertia load and any further contraction would leave slack or lash between the parts of the valve train. When this happens the spring 21 in the adjuster, which then has no axial load on it, can take over and due to the torsional load thereon wind the body downwards on the threads 15 and 17 so as to take up any slack or lash. So far, the operation of the adjuster is straight forward. The difficult part, however, of any mechanical lash adjuster is getting it to go in the opposite direction or "leakdown" so as to take care of too much expansion in the parts which would otherwise retain the valve off its seat. The present invention provides compensation for any such expansion because the small diametrical clearance C allows slipping to take place in these threads at the start of the valve lift cycle until this clearance C is closed in one direction. The rest of the slipping then takes place between the rocker and the body until full valve lift is reached. At some point during valve closing slipping also takes place in the threads 15 and 17 in the opposite direction. The threads 15, 17 have a helix angle so that the body will just not screw down under direct load; however, when the aforementioned slipping is taking place as described the body will screw down a minute amount per cam revolution. The reason for this is easier to demonstrate than to describe but depends on the condition that when a body is dragged across a slightly inclined plane it tends to slip down the plane at the same time. Since the loads on the rocker are high during valve operation this effect can overcome the force of spring 21 in the adjuster.

From the foregoing description it will be appreciated that the lateral sliding which takes place between the threads 15, 17 is caused by the rocking action of the rocker 7 which tends to cock or move the body 16 laterally in one direction or the other relative to the nut 14 depending on the direction of rocking of the rocker 7. This movement of the body 16 relative to the nut 14 is, of course, made possible by the aforementioned clearances C and K. It is important to realize that it is the

rocking action of the rocker 7 as it rocks under the forces exerted by the push rod 8 and the valve stem 5 which causes the sliding movement between threads 15, 17 and makes this so-called "leakdown" possible to compensate for expansion of the parts in the valve train which might otherwise maintain the valve off its seat.

Turning now to the modification shown by Figure 4, like numerals are used to indicate like parts in this modification and the embodiment shown in Figure 1. In Figure 4 it will be observed that the spring 21 has its ends 22 and 23 anchored in the body 16 and nut 14 in the same manner as the embodiment shown in Figure 2 except that there is no direct communication of oil to the loose threads 15, 17.

Again, as the case of the modification of Figure 4, like parts in the modification of Figure 5 of the embodiment shown in Figure 2 are indicated by the same numerals. It will be noted, however, that in the embodiments shown in Figures 2 and 4 the spring 21 is attached to the body 16 and the nut 14 by inserting the ends into small drilled holes. It has been found that these holes are hard to drill in production. Therefore, in the modification of Figure 5, the body 16 and nut 14 are provided with lower and upper cup-shaped depressions 29 and 30. The diameters of these cup-shaped depressions are less than the free outside diameter of the spring 21 so that the ends of the springs are compressed inwardly. In addition, the spring 21 has a right-hand spiral so that the twist in it tends to unwind it. This also helps to insure that the ends of the spring do not slip in the cups.

Figure 6 illustrates a further detail of the modification of Figure 5 which comprises a retaining cap or piece 31 which snaps into place on the upper end of the body 16 so as to limit the body 16 from screwing down too far on the nut 14.

Again, in Figure 7, like numerals are used to designate like parts in the embodiments shown in Figures 2, 4 and 5. In this embodiment the lower end of the spring 21 is frictionally seated in an upwardly facing cup-like depression 32 in the upper end of the body 16 which is again of lesser diameter than the free outside diameter of spring 21. This spring also has a right-hand spiral so that the twist in it tends to unwind it. The upper end of spring 21 has an end 33 turned in and anchored in a tapped hole 34 in the upper end of nut 14, immediately below the cap 35 so that the spring acts as a retainer to prevent the body 16 from screwing down too far. In the embodiment of Figure 7 oil is supplied to the center of the threads 15, 17 via port 28 and annular clearance 36 and port 37 at the center of threads 15, 17 for more positive lubrication. These threads have a very high thread angle and a crown on the flank of the nut thread to improve slipping between these threads.

I claim:

1. A combined rocker fulcrum and valve train clearance regulator wherein the regulator function is dependent upon movement of the rocker at the fulcrum comprising a pair of members loosely threaded together and having diametrical clearance between the threaded portions thereof to allow the members to cock in opposite directions relative to each other, resilient means acting between said members to unthread them, one of said members being fixed, the other of said members being arranged to have a rocker mounted thereon so as to exert thrust thereagainst in opposition to said resilient means, the other of said members being arranged to have such rocker oscillate thereon about a point fixed relative thereto so that the motion thereof causes cocking of said members in opposite directions relative to each other and sliding movement between said threaded portions tending to take up said diametrical clearance in one direction or the other and thereby induces relative axial adjustment between said members.

2. In combination with a rocker having an opening ex-

tending therethrough in the thrust direction, clearance regulator supporting means for the rocker comprising a first threaded member extending through said opening with sufficient clearance to accommodate rocking movement of said rocker, a second threaded member telescopically associated with said first member and loosely threaded thereon through which said first member extends, said rocker and said second member having co-acting spherical bearing surfaces defining the rocking axis of said rocker, resilient means acting between said members tending to unthread them, said members having lateral clearance between the associated threaded portions thereof to allow the members to cock in opposite directions relative to each other such that the rocking action of said rocker on said second member through said spherical bearing surfaces causes cocking and consequent lateral sliding between said threaded portions which induces relative axial adjustment between said members.

3. In combination with a rocker having an opening extending therethrough in the thrust direction, a clearance regulator having combined therewith supporting means for the rocker comprising a first member extending through said opening with sufficient clearance to accommodate rocking movement of said rocker, said first member having an enlarged externally threaded portion thereon beyond the thrust side of said rocker, a second member telescopically associated with said first member and having an upper internally threaded portion loosely threaded on said externally threaded portion and forming an annular chamber around said first member between said rocker and said threaded portions, said rocker and said second member having co-acting bearing surfaces defining the rocking axis of said rocker, said first member having an oil-conducting passage extending in the direction of thrust through said rocker, said first member having a port connecting said chamber to said passage, an oil passageway in said enlarged threaded portion communicating with said threaded portions and having an axially extending leg leading from said chamber, a helical coil spring around said first member in said chamber having an axially extending end of smaller diameter than the diameter of said axially extending leg and anchored therein, the opposite end of said spring being anchored to said second member, said spring being torsionally loaded so as to tend to unthread said members, said members having lateral clearance between the threaded portions thereof to allow the members to cock in opposite directions relative to each other such that the rocking action of said rocker on said second member causes cocking and consequent lateral sliding between said threaded portions which induces relative axial adjustment between said members.

4. In combination with a rocker having an opening extending therethrough in the thrust direction, a clearance regulator having combined therewith supporting means for the rocker comprising a first member extending through said opening with sufficient clearance to accommodate rocking movement of said rocker, said first member having an enlarged externally threaded portion thereon beyond the thrust side of said rocker, a second

5 10 15 20 25 30 35 40 45 50 55 60

member telescopically associated with said first member and having an upper internally threaded portion loosely threaded on said externally threaded portion and forming an annular chamber around said first member between said rocker and said threaded portions, said rocker and said second member having co-acting bearing surfaces defining the rocking axis of said rocker, an upwardly facing annular spring seat in the bottom of said second member around said first member, a downwardly facing annular spring seat at the bottom of said externally threaded portion, a helical coil spring in said chamber about said first member of greater normal diameter than said spring seats having its opposite ends frictionally engaged in said seats and torsionally loaded so as to tend to unthread said members, said members having lateral clearance between the threaded portions thereof such that the rocking action of said rocker on said second member causes sliding between said threaded portions and induces relative axial adjustment between said members.

5. In combination with a rocker having an opening extending therethrough in the thrust direction, a clearance regulator having combined therewith supporting means for the rocker comprising a first member having a shank extending through said opening with sufficient clearance to accommodate rocking movement of said rocker, said first member having an externally threaded portion on said shank beyond the thrust side of said rocker, a second member telescopically associated with said first member and having an upper externally threaded portion loosely threaded on said externally threaded portion, said rocker and said second member having co-acting bearing surfaces defining the rocking axis of said rocker, said first member having a cap thereon above said threaded portions, the upper end of said second member forming an annular upwardly facing spring seat above said threaded portions, a helical coil spring of larger normal diameter than said annular seat having a lower end fixed therein, the upper end of said spring abutting said cap and having a laterally extending end anchored in said first member immediately below said cap, said spring being torsionally loaded so as to tend to unthread said members, said members having lateral clearance between the threaded portions thereof such that the rocking action of said rocker on said second member causes sliding between said threaded portions and induces relative axial adjustment between said members.
